Inventor:

Herman Berglund,
by *Albert S. Darn*
His Attorney.

UNITED STATES PATENT OFFICE.

HERMAN BERGLUND, OF BROOKLYN, NEW YORK, ASSIGNOR TO GENERAL ELECTRIC COMPANY, A CORPORATION OF NEW YORK.

PAPER-BREAK DETECTOR SWITCH.

Application filed May 13, 1922. Serial No. 560,858.

Paper break detector switches have heretofore been provided for opening the control circuit of the driving motor of a printing press or the like when the web breaks, so as to deenergize the motor and stop the equipment. In order to again start the equipment and before threading the paper through the press, some arrangement must be provided for restoring the control of the driving motor, despite the operation of the paper break detector switch. Arrangements have heretofore been provided for effecting this result, but these prior arrangements have been complicated and expensive.

One of the objects of my invention is to provide a paper break detector switch arranged so that when the paper breaks, the switch mechanism will be operated to deenergize the driving motor and when it is desired to again start up the press, control is restored to the ordinary motor controller by simply raising the finger which writes on the paper out of cooperative relation with the paper and holding the finger in that position by suitable means, as for example, a spring catch. This, and other objects of my invention, as will be in part apparent to those skilled in the art and in part fully explained hereinafter, are accomplished by the paper break detector switch shown in the accompanying drawings which show an embodiment of the invention for the purpose of explaining the features thereof.

Referring to the drawing Fig. 1 is a side view of a paper break detector switch with the finger which writes on the web of paper in its normal position on the web of paper; Fig. 2 is a similar view showing the relative positions of the parts when the paper breaks; Fig. 3 is a top plan view of the switch shown in Fig. 1; Fig. 4 shows the manner in which the finger which writes on the paper and the arm which cooperates with the switch mechanism are held so that the press may be restarted and the paper threaded through the press after the web is broken; Fig. 5 is a very simplified diagram of a system of motor control for the driving motor of the press.

Referring to the drawings, the paper break detector switch therein shown comprises normally closed switch mechanism having a contact disc 10 which is adapted to cooperate with a pair of stationary contacts 11 in the control circuit of the motor. This

contact disc is biased to the closed position of the contacts by means of the coil spring 12. The button 13 of insulating material is connected with the disc 10 for the purpose of moving the disc out of engagement with its stationary contacts against the action of the spring 12. The member 14 is pivoted at 15 so as to be biased by gravity to a position at which the arm 16 will cooperate with the button 13 so as to open the switch and at which the finger 17 which writes on the paper will be held in yielding engagement with the web of paper. On the opposite side of the pivot point 15 to the arm 16 there is provided a rounded projection 18 which cooperates with a spring catch 19 so as to hold the member 14 in the position shown in Fig. 4.

As thus constructed and arranged the operation of my invention is as follows: As long as the web of paper is not broken, the finger 17 will rest on the web of paper so as to hold the arm 16 out of cooperative relation with the button 13 and permit the switch contact disc to be held in its normally closed position. When the paper breaks as shown in Fig. 2, the member 14 drops due to the bias of gravity and the arm 16 makes engagement with the button 13 so as to move the disc 10 out of engagement with the stationary contacts 11. The electromagnetic line switch 20 is thereby deenergized and the motor 21 is disconnected from the source of supply 22. It will be understood by those skilled in the art that in the ordinary equipment for driving a printing press, a controller of some suitable sort will be provided for starting, stopping and regulating the speed of the driving motor 21. I have not shown such a controller and its connections since those skilled in the art will readily supply a suitable arrangement. The pilot switch 23 will then be opened so that when the detector switch is closed, the starting of the motor will be under the control of the operator. In order to restart the motor and thread the paper through the press, all that need be done is to raise the member 14 out of cooperation with the web of paper to the position shown in Fig. 4 at which the spring catch 19 makes a holding engagement with the projection 18. The finger of the member 14 is thus moved out of the way of the paper and does not interfere with threading the paper through the press, and furthermore

the contact disc is permitted to assume its normal position in engagement with the stationary contacts 11. The operator may start the press at any time desired by simply re-closing the pilot switch 23.

The device is neat and compact and cheap to manufacture. The single casting 24 with its cover 25 on which the spring catch 19 is mounted serves as a casing or container for the switch parts and this casting also serves as a coupling or junction for the cable conduits 26 and 27 which protect the wires leading to the switch. The device is very convenient in that when the paper breaks the pressman need do nothing more than turn the detector arm back until it is caught by its spring catch and thus held in its retracted position, before starting the motor and threading the paper through the press.

In accordance with the provisions of the patent statutes I have described the principle of operation of my invention together with the apparatus which I now consider to represent the best embodiment thereof but I desire to have it understood that the apparatus shown is only illustrative and that the invention may be carried out by other means.

What I claim as new and desire to secure by Letters Patent of the United States, is:

1. A paper break detector switch comprising a movable member adapted to rest on the paper, switch mechanism controlled thereby, and means for holding the said member out of cooperative relation with the said switch mechanism and out of engaging relation with the paper.

2. A paper break detector switch comprising a pivoted member the free end of which

is adapted to rest on the paper, switch mechanism biased to one position and operated to another position by the said member when the paper breaks, and a spring catch cooperating with the said member for holding the same out of cooperative relation with the said switch mechanism and out of engaging relation with the paper.

3. A paper break detector switch comprising normally closed switch mechanism, a pivoted member having an arm biased to open the said switch mechanism and a finger adapted to rest on the paper so as to hold the said arm out of engagement with the said switch mechanism until the paper breaks, a projection on the said member, and a spring catch cooperating with the said projection to hold the said finger out of cooperation with the paper and the said arm out of cooperative relation with the said switch mechanism.

4. A paper break detector switch comprising a casing arranged to form a junction for a cable conduit, an arm having one end pivoted to the said casing and the other end thereof arranged to rest on the paper, switch mechanism within the said casing normally out of cooperative relation with the said arm when the arm is held by the paper and arranged to be operated by the said arm when the paper breaks, and means mounted on the said casing cooperating with the said arm to hold the same out of cooperative relation with the said switch mechanism and out of engaging relation with the paper.

In witness whereof, I have hereunto set my hand this 2d day of May, 1922.

HERMAN BERGLUND.
